FLUID PRESSURE BRAKING APPARATUS

Theophile Tarisien, Livry-Gargan, France, assignor to Westinghouse Air Brake Company, Wilmerding, Pa., a corporation of Pennsylvania

Application August 4, 1933, Serial No. 683,586
In Great Britain August 13, 1932

6 Claims. (Cl. 303—84)

This invention relates to fluid pressure braking apparatus of the kind comprising a triple or other form of distributing valve device adapted to effect the application of the brakes by the supply of fluid under pressure to the brake cylinder or cylinders of the apparatus in two stages, during the first of which the supply of fluid is relatively unrestricted so as to cause a rapid application of the brake blocks to the wheels, while during the second stage the flow of fluid to the brake cylinder or cylinders is relatively restricted so as to cause a gradual building up of the desired pressure.

Distributing valves of this character as hitherto constructed have usually comprised a regulating valve interposed in the path of the flow of fluid to the brake cylinder or cylinders, this valve being normally maintained in its open position by an abutment subject on one side to the action of a controlling spring. The opposite side of the abutment is arranged to be subject to the pressure obtaining in the brake cylinder, so that, as soon as this pressure has built up to a value sufficient to overcome the action of the controlling spring the abutment is moved to permit closure of the regulating valve, the subsequent flow of fluid under pressure to the brake cylinder taking place through a relatively restricted port.

The invention has for its principal object to provide an improved regulating valve of the character above indicated in which the abutment of the valve is arranged to be subject to a controlling fluid pressure which is a definite predetermined fraction of the normal fluid pressure obtaining in the system, thus dispensing with the use of a controlling spring as has hitherto been customary.

In order that the invention may be readily understood a preferred embodiment thereof will now be described with reference to the accompanying drawing as applied to a triple valve device of otherwise known construction.

Referring now to the single figure of the accompanying drawing, the triple valve comprises a casing 1 containing a valve chamber 2 and a piston chamber 3, the latter containing a piston 4 adapted to actuate a slide valve 5 provided with the usual ports and cavities and containing a graduating valve 6. Mounted on one side of the casing is an accelerating bulb or chamber 7 which communicates through a passage 8 with a port 9 in the seat of the slide valve. In the release position of the triple valve piston, as shown in the single figure of the drawing the port 9 is arranged to be in communication with the atmosphere by

way of a cavity 10 in the slide valve 5 and an atmospheric port 11. The valve chamber 2 is in open communication with the auxiliary reservoir (not shown in the drawing) in the usual manner, the piston chamber 3 being in communication with the train pipe 24 of the apparatus. A port 12 in the triple valve casing 1 communicates with the brake cylinder (not shown in the drawing) and the said casing is provided with a rotary plug cock 13 having a calibrated orifice 14 therein. Arranged below the plug cock 13 is a controlling valve 15 which is normally open, and the seat 16 of the said controlling valve is provided with a restricted by-pass orifice 17.

The controlling valve 15 is arranged to be normally maintained in its open position by means of a diaphragm 18 subject on its upper side to the fluid pressure conditions obtaining in a diaphragm chamber 19 connected through a passage 20 in the triple valve casing with the port 12 communicating with the brake cylinder, the diaphragm 18 being subject on its lower side normally to the fluid pressure obtaining in a diaphragm chamber 21 which under release conditions as shown in the single figure of the drawing is in communication through a passage 22 in the triple valve casing 1 and a port 23 in the slide valve seat with the slide valve chamber 2. Under application conditions the diaphragm chamber 21 is in communication with an expansion chamber 25 through passages 22 and 26 in the triple valve casing and a cavity 27 in the slide valve 5, which cavity serves under release conditions as shown in the drawing to establish communication between the expansion chamber 25 and an atmospheric port 28.

The operation of the apparatus is as follows:

Under release conditions the triple valve piston and slide valve are in their left hand positions as shown in the drawing in which the graduating valve 6 is closed and the brake cylinder is in communication with an atmospheric port 29 through a recess 30 in the slide valve. Moreover the accelerating bulb or chamber 7 is in communication with the atmospheric port 11, as described hereinbefore and a port 31 in the slide valve seat which is in communication with the train pipe 24 is blanked by the slide valve 5; the diaphragm chamber 21 is in communication with the slide valve chamber 2 and the expansion chamber 25 with the atmospheric port 28.

When the train pipe pressure is reduced in order to effect an application of the brakes, the triple valve piston 4 is moved to the right, first lifting the graduating valve 6 from its seat and

then shifting the slide valve 5 to its right hand or application position, the movement of the piston 4 and slide valve 5 being accelerated owing to communication being established between the 5 port 31 in the slide valve seat which is in communication with the train pipe 24, and the port 9 in the slide valve seat which is in communication with the bulb 7, this communication being established through the recess 10 in the slide 10 valve 5. In the right hand or application position of the slide valve 5 the recess 27 in the slide valve establishes communication between the expansion chamber 25 and the diaphragm chamber 21 with the result that the diaphragm 18 15 is subject underneath to only a fraction of the auxiliary reservoir pressure, the value of this fraction being dependent upon the relative volumes of the diaphragm and expansion chambers 21, 25. In the application position of the slide 20 valve fluid under pressure is supplied from the auxiliary reservoir through the slide valve chamber 2 and past the unseated graduating valve 6 to the brake cylinder through a passage 32 in the casing 1 of the triple valve. The flow of fluid 25 to the brake cylinder follows two paths, the first traversing the calibrated orifice 14 in the plug cock 13 and the second traversing the controlling valve 15 referred to hereinbefore and the calibrated orifice 17 in the seat 16 of said valve. 30 Fluid is therefore supplied relatively rapidly to the brake cylinder so as to apply the brake blocks, to the wheels and as soon as the value of the fluid pressure obtaining in the brake cylinder is slightly greater than the value of the fraction of the 35 auxiliary reservoir pressure obtaining in the diaphragm chamber 21, the diaphragm 18 is flexed downwardly and permits the controlling valve 15 to seat. Thereafter fluid is supplied to the brake cylinder through the two calibrated orifices 14 and 17 only so as gradually to build up the braking pressure.

It will be evident that the invention is not limited to the particular construction and arrangements of the parts hereinbefore described which 45 may be varied as desired to suit particular requirements without exceeding the scope of the invention.

Having now described my invention, what I claim as new and desire to secure by Letters Patent is:—

1. A valve device for regulating the flow of fluid under pressure to the brake cylinder of fluid pressure braking apparatus comprising in combination a movable abutment subject on one side to the pressure in the brake cylinder, means for subjecting the opposite side of said abutment to a pressure which is substantially constant while the brakes are being applied and which is a predetermined fraction of the normal pressure in said braking apparatus, and a valve operated by said abutment for controlling the flow of fluid to the brake cylinder.

2. A valve device for regulating the flow of fluid under pressure to the brake cylinder of fluid pressure braking apparatus comprising in combination a movable abutment subject on one side to the pressure in the brake cylinder, means for subjecting the opposite side of said abutment during the release of the brakes, to the normal pressure obtaining in the apparatus, means for subjecting this side of the abutment to a substantially constant pressure which is a predetermined fraction of said normal pressure during the application of the brakes, and a valve operated by said

abutment for controlling the flow of fluid to the brake cylinder.

3. A valve device for regulating the flow of fluid under pressure to the brake cylinder of fluid pressure braking apparatus comprising in combination a movable abutment subject on one side to the pressure in the brake cylinder, means for subjecting the opposite side of said abutment, during the release of the brakes, to the normal pressure obtaining in the apparatus, means for subjecting this side of said abutment to a different pressure from said normal pressure which is substantially constant during the application of the brakes, and a valve operated by said abutment for controlling the flow of fluid to the brake cylinder.

4. The combination in fluid pressure braking apparatus of a distributing valve having a release position and an application position, a regulating valve for controlling the supply of fluid under pressure to the brake cylinder of the apparatus through said distributing valve, a movable abutment for operating said regulating valve and subject on one side to the pressure in said brake cylinder, means for supplying fluid at one predetermined pressure to the opposite side of said abutment when the distributing valve is in its release position and means for subjecting the opposite side of said abutment to a different predetermined fluid pressure which remains substantially constant when said distributing valve is in its application position.

5. The combination in fluid pressure braking apparatus of a distributing valve having a release position and an application position, a regulating valve for controlling the supply of fluid under pressure to the brake cylinder of the apparatus through said distributing valve, a movable abutment for operating said valve and subject on one side to the pressure in said brake cylinder, a chamber in communication with the opposite side of said abutment, means for supplying fluid at a predetermined pressure to said chamber when said distributing valve is in its release position, a second chamber and means for cutting off the supply of fluid to said first chamber and for establishing communication between said chambers when said distributing valve is in its application position to provide a substantially constant pressure less than said predetermined pressure in the chamber in communication with said opposite side of the abutment.

6. The combination in fluid pressure braking apparatus of a distributing valve having a release position and an application position, a regulating valve for controlling the supply of fluid under pressure to the brake cylinder of the apparatus through said distributing valve, a movable abutment for operating said valve and subject on one side to the pressure in said brake cylinder, a chamber in communication with the opposite side of said abutment, a second chamber, means for supplying fluid under pressure to said first chamber and for venting said second chamber when said distributing valve is in its release position and means for cutting off the supply of fluid under pressure to said first chamber and for establishing communication between said chambers when said distributing valve is in its application position to provide in said first chamber a pressure which remains substantially constant while the brakes are applied.
